UNITED STATES PATENT OFFICE.

EDWARD PAUL BELZ, OF ATHENS, WISCONSIN.

DESIGN FOR A CHAIN-TRACE LINK.

55,117.

Specification for Design.

Patented May 11, 1920.

Application filed April 25, 1919. Serial No. 292,753. Term of patent 14 years.

To all whom it may concern:

Be it known that I, EDWARD PAUL BELZ, a citizen of the United States, residing at Athens, in the county of Marathon and State of Wisconsin, have invented a new, original, and ornamental Design for a Chain-Trace Link, of which the following is a specification, reference being had to the accompanying drawing, forming part thereof.

Figure 1 is a perspective view of the new design.

Fig. 2 is a top plan view; and

Fig. 3 is a side elevation thereof.

I claim:

The ornamental design for a chain-trace link as shown.

Signed at Athens, in the county of Marathon and State of Wisconsin.

EDWARD PAUL BELZ.
